BRACELET OR THE LIKE

Abraham J. Slovitt, New York, N. Y.

Application April 22, 1954, Serial No. 30,135

Term of patent 3½ years

(Cl. D45—4)

FIG. 2.

To all whom it may concern:

Be it known that I, Abraham J. Slovitt, a citizen of the United States of America and a resident of the city and State of New York, county of Kings, have invented a new, original, and ornamental Design for a Bracelet or the like, of which the following is a specification, reference being had to the accompanying drawing, forming part thereof.

Fig. 1 is a front elevational view of bracelet or the like embodying my new design; and

Fig. 2 is a top view thereof.

I claim:

The ornamental design for a bracelet or the like, substantially as shown.
